UNITED STATES PATENT OFFICE

2,564,584

DEAERATING FEED-WATER HEATER

Joseph F. Sebald, Bloomfield, N. J., assignor to
 Worthington Pump and Machinery Corporation,
 Harrison, N. J., a corporation of Delaware

Application October 5, 1948, Serial No. 52,869

7 Claims. (Cl. 261—115)

1

This invention relates to apparatus for heating and degasifying liquids, particularly such apparatus known in the art as "jet" type heaters wherein the water to be heated and degasified is sprayed into or mixed in direct contact with the heating steam and is projected into a low pressure area for "flashing" or reboiling for heating the water and separating the non-condensable gases, particularly oxygen, from the heated water. Such heaters, while all of the common general type, are known in the trade as the atomizing type heater, shown for example in prior Patents 2,315,227 of March 30, 1943, and 2,321,839 of June 15, 1943, and the intimate mixing type shown for example, in Patents 2,308,719 and 2,308,721 of January 19, 1943.

In water heaters of these direct contact types all of the heating steam is not condensed in the heating and degasifying operation of the apparatus and vent condensers are employed such as shown at U in Patent 2,315,227; at 31' in Patent 2,321,839; at 30 in Figure 1 of Patent 2,308,719, and at 5 in Patent 2,308,721 in the apparatus for condensing the residual steam and cooling the non-condensable gases which later are released to atmosphere, while the condensed steam is returned as liquid condensate to the apparatus. Such vent condensers which are universally employed with water heaters and deaerators of the types above referred to, as well as with those of the earlier tray type of heater are surface type condensers and are relatively expensive to manufacture, are heavy and materially increase the space required for installation of the apparatus. These qualities are undesirable in modern power plant construction and particularly in marine power plants, wherein space on shipboard is at a premium and in which it is desired to keep the weight of such equipment or apparatus at a minimum.

An object of the present invention is to provide water heating and deaerating apparatus which embodies means within the housing of the apparatus for condensing the residual steam, eliminating the surface type vent condenser and its cooperating piping, without eliminating its functions, thereby materially reducing the cost of the apparatus, reducing its weight and the space required for its installation.

Another object of the present invention is to provide in a direct contact feedwater heater and deaerator for heating water and removing non-condensable gases therefrom, means which will direct the residual vapors through an accumulation of the partially heated water and from thence

2

into direct contact with the incoming sprays of cold water at the coldest part of the apparatus for condensing the residual steam and cooling the non-condensable gases, and further to provide means for the escape of the non-condensable gases and the return of the condensed residual vapor or steam to an appropriate point in the apparatus for mixture with the water being treated.

In the present application, the term "residual vapors" or "residual steam" is used to define the steam and non-condensable gases which are not condensed during the heating and degasifying of the water by the normal operation of the apparatus, i. e., the residual vapors which have previously to the present invention been passed to a vent condenser for condensation and cooling.

With these and other objects in view, as may appear from the accompanying specification, the invention consists of various features of construction and combination of parts, which will be first described in connection with the accompanying drawings, showing a deaerating feedwater heater of a preferred form embodying the invention, and the features forming the invention will be specifically pointed out in the claims.

In the drawings:

Figure 1 is a vertical section through the improved deaerating feedwater heater.

Figure 2 is a fragmentary horizontal section through the feedwater heater showing in top plan the structure for spraying the cold water into the apparatus.

Figure 3 is a section through the spray head structure taken on the line 3—3 of Figure 2.

Figure 4 is a horizontal section through the apparatus taken on the line 4—4 of Figure 1.

Referring more particularly to the drawings, the improved feedwater heater and deaerator comprises a shell 1 including therein a first or initial heating chamber 2 and a second or subsequent low pressure heating and degasifying chamber 3. The water to be heated enters the apparatus through the water inlet pipe 4 and passes into the spray head 5 located in the initial heating chamber 2. The spray head 5 is a hollow body and has a plurality of spray valves 6 of any approved construction which may be purchased upon the open market, connected thereto, which spray valves spray the cold water in thin fine streams upwardly into the chamber 2 as is clearly shown in Figure 1 of the drawings. The water sprayed through the chamber 2 strikes against the inner surface of the top 7 of the housing 1 and against the vertical annular partition 8. The water striking against the inner surface

of the top 1 of the housing 1 and against the vertical annular partition 8. The water striking against the inner surface of the top 1 of the housing 1 rains downwardly through the initial heating chamber 2 and falls upon the inverted substantially conical partition 9. The partition 9 has its outer edge attached to a second annular vertical partition 10 and thus with the partitions 8 and 10 forms the confines of the initial heating chamber 2. A third vertical annular partition 11 is provided and has its lower edge attached to the inverted substantially conical partition 9. The annular vertical partitions 8, 10, and 11 cooperate to form an annular water receiving channel 12 with an open water inlet space between the partitions 8 and 11 so that some of the water sprayed against the annular partition 8 will run down the partition and fall or pass into the annular water retaining space 12.

The water which rains upon the inverted substantially conical partition 9 drains down to the apex of the partition and passes into a vertical conduit 13 from which it flows into the mixing spray head structure 14.

Steam utilized in heating and deaerating the water enters the apparatus through the steam inlet 15 and passes into the steam conducting space 16 formed between the partition 9 and a second inverted frusto-conical partition 17 from the space or passage 16. The steam enters a downward passage 18 formed about the downward water passage by a substantially cylindrical conduit 19. From the passage 18 the steam enters the mixing spray structure 14.

The mixing spray structure 14 includes the outer cup-like body 20 and the inner cup-like body 21 placed therein and spaced from the walls of the outer body 20 to provide a passage 22, the section 23 of which forms an eductive passage through which the water is picked up by the inductive force of the steam passing through the passage 24 formed within the inner cup-like body 21. The steam and water issue respectively from the passages 24 and 23 into the mixing passage 25 where the steam and water are intimately mixed. The passage 25 gradually increases in cross sectional area from a predetermined point in its length to its outlet and the mixed steam and water from this mixing passage are sprayed or projected into the subsequent or low pressure chamber 3 within the housing 1. During such projection the mixed stream of steam and water is broken up by its projection against the under surface of the partition 17 and the baffles 27. Also, the mixed steam and water together with non-condensable gases are projected in a substantially atomized form into the low pressure chamber 3. The non-condensable gases and the residual steam, constituting the residual vapors are released from the heated water and such steam as has been condensed during the mixing operation and the projection thereof into the chamber 3. The heated water and condensate falls into the lower part of the housing 1 from which it is withdrawn through a suitable outlet 28. The residual vapors, constituting the residual or non-condensed steam and the non-condensable gases, passes upwardly through the chamber 3 and downwardly into the annular water retaining space or channel 12 through the annular steam inlet 29. The steam inlet 29 is formed between the partitions 8 and 10. The residual vapors pass downwardly and upwardly, that is, in a sinuous path through the water collected in the

annular water retaining space or channel 12 whereby part of the steam is condensed. The remaining residual steam and the non-condensed vapors pass upwardly out of the annular space or channel 12 into the initial heating chamber 2 carrying with them by a blowing action some of the water from the annular channel 12. Owing to the fact that the water sprayed by the spray head 5 is relatively cold, the coldest points in the initial heating chamber 2 will be at and immediately surrounding the spray head 5 and, consequently, the steam and non-condensable gases will flow in counter-current flow paths to the direction of the sprayed water towards the coldest part of the chamber 2, and practically all of the steam will thus be condensed with the non-condensable gases passing through the vent passage 30 to atmosphere. The vent passage 30 is shown as formed by a tubular conduit 31 which extends downwardly from the top of the shell 1 to a point in spaced close proximity to the top of the spray head 5. Thus the non-condensable gases will be materially cooled and their volume reduced before they are vented to atmosphere.

The annular water retaining space or channel 12 is divided into a plurality of independent compartments by gusset plates 32 as clearly shown in Figure 4 of the drawings so as to prevent short circuiting of water and steam through parts of the annular space or channel in which water might not be contained or an insufficient amount contained therein as a result of non-level mounting of the apparatus or during rolling and pitching of a ship when the deaerating feedwater heater is employed on shipboard.

Some of the residual steam and non-condensable gases may pass around the spray head 5 into the space in the initial heating chamber 2 below the spray head and for the purpose of extracting such steam and non-condensables back into the upper part of the chamber for condensation or venting to atmosphere the spray head 5 is provided with a plurality of ducts or passages 33 extending therethrough. These ducts or passages 33 are shown as alternately spaced relative to the spray heads 6, but they may be located at any suitable or desirable points and may be truly vertical or angular, as desired or as best designed practices dictate. The cold water being sprayed into the chamber 2 above the spray head 5 will create, together with the relative coldness of the space directly above the spray head a sucking action on non-condensable gases and steam in the space below the spray head 5 and draw the same into the space above the spray head 5.

The spray head 5 is also provided with a centrally located tapering opening 34 extending therethrough which gradually decreases in cross sectional area from the top of the spray head 5 to the bottom thereof and which aligns with the vent conduit 31. A tube 35 extends from the lower outlet end of the opening 34 downwardly through the water conduit 13 to a point in the conduit below the normal water level in the conduit and in the mixing spray head 14 so as to permit any condensate or water which falls upon the top of the spray head 5 to pass downwardly into the mixing head 14 for mixture with the water entering the mixing head. By extending the tube 35 below the normal water level in the mixing head 14 back-flow of water, air or steam through the tube 35 is prevented.

With the structure of deaerating water heater

shown and described herein practically all the steam entering the apparatus will be condensed and the employment of a vent condenser, as has been the usual practice heretofore, is eliminated with the elimination of its resulting disadvantages such as increased cost, increased weight and space requirements.

It will be understood that the invention is not to be limited to the specific construction or arrangement of parts shown, but that they may be widely modified within the invention defined by the claims.

What is claimed is:

1. In a water heater and degasifying apparatus, a housing, an initial stage heating chamber in said housing, a subsequent stage treatment chamber in said housing, means for introducing steam direct to said subsequent steam treatment chamber, means for introducing the water to be heated and degasified into said initial stage chamber including a hollow spray head, a plurality of spray valves carried by said head, said head having a plurality of passages extending therethrough which are isolated from the interior of the head to permit passage of steam and non-condensable gases through the spray head without contact with water in the head.

2. In a water heating and degasifying apparatus, a housing having means therein forming an initial stage heating chamber and a subsequent stage treatment chamber, means for spraying water to be treated into said initial stage chamber, means for delivering mixed steam and water to said subsequent treatment chamber, the means for delivering steam and water to said subsequent stage treatment chamber including an inclined baffle forming the bottom of said initial stage chamber, a pair of spaced annular baffles rising from said inclined baffle at and near its outer edge and forming an annular trough spaced inwardly from the housing to form a passage of communication between said initial stage chamber and said subsequent treatment chamber, a third annular baffle carried by said housing and positioned to direct some of the water sprayed into the initial stage heating chamber into said annular trough to provide a depth of water in a trough, said third annular baffle extending into the trough below the normal level of water therein and intermediate of the pair of spaced annular baffles to form an inlet passage to the trough having communication with the passage of communication about the trough and an outlet passage opening into the initial stage treatment chamber whereby non-condensables and residual steam passing from said subsequent treatment chamber to said initial stage chamber must pass through the water in said trough.

3. A water heating and degasifying apparatus as claimed in claim 2 wherein said inclined baffle has a central opening therein to permit water to flow from said initial treatment chamber to said means for delivering steam and water to said subsequent treatment chamber.

4. A water heating and degasifying apparatus as claimed in claim 2 including a non-condensable gas escape conduit in said housing and having

its inlet opening into said initial stage chamber in relatively close spaced relation with said spray head.

5. A water heating and degasifying apparatus as claimed in claim 2 wherein said means for introducing water into said initial treatment chamber includes a hollow spray head located within the initial treatment chamber, a plurality of spray valves carried by said head, said head having a plurality of transverse passages extending therethrough which are isolated from the interior of the head to permit passage of steam and non-condensable gases through the spray head without contact with water in the head.

6. A water heating and degasifying apparatus as claimed in claim 2 wherein said means for introducing water into said initial stage chamber includes a hollow spray head located within the initial stage chamber, a plurality of spray valves carried by said head, said spray head having a transversely extending condensate drain passage extending therethrough and isolated from the interior of the head to permit passage of condensate through the spray head without contact with water in the spray head, said spray head having an additional plurality of passages extending therethrough in spaced relation to said condensate drain passage and isolated from the interior of the head to permit passage of steam and non-condensable gases through the spray head without contact with water in the spray head.

7. A water heating and degasifying apparatus as claimed in claim 2 wherein said means for introducing water into said initial stage chamber includes a hollow spray head located within the initial stage chamber, a plurality of spray valves carried by said head, said spray head having a transversely extending condensate drain passage extending therethrough and isolated from the interior of the head to permit passage of condensate through the spray head without contact with water in the spray head, a conduit pipe having its inlet placed to receive condensate from said condensate drain passage and its outlet extending into the means for introducing water from said initial stage chamber into said subsequent stage chamber sufficient distance to submerge the outlet end of the conduit to prevent backflow of steam or water through the conduit from said subsequent stage chamber to said initial stage chamber.
